UNITED STATES PATENT OFFICE.

CHARLES B. KIRKHAM, OF GARDEN CITY, NEW YORK, ASSIGNOR TO CURTISS AERO-PLANE AND MOTOR CORPORATION, A CORPORATION OF NEW YORK.

LUBRICATING DEVICE FOR INTERNAL-COMBUSTION ENGINES.

1,404,861.

Specification of Letters Patent. Patented Jan. 31, 1922.

Application filed May 31, 1918. Serial No. 237,494.

To all whom it may concern:

Be it known that I, CHARLES B. KIRKHAM, a citizen of the United States, residing at Garden City, Long Island, in the county of 5 Nassau and State of New York, have invented certain new and useful Improvements in Lubricating Devices for Internal-Combustion Engines, of which the following is a specification.

10 This invention relates to internal combustion engines and particularly to lubricating features thereof.

The object of the invention is the provision of improved lubricating devices and 15 the arrangement thereof whereby the lubricant is freely circulated through the moving parts of the motor and is maintained free of foreign and contaminating substances and is at all times in a thoroughly cleansed condition, it being thereby possible to use the 20 lubricant over and over again without undue impairment of its lubricating qualities. I have illustrated my invention as embodied in a motor having a sump in the bottom of 25 the crank case and a pump located in the sump which drains the used lubricant downwardly from the moving parts and forces the same upwardly through the manifolds leading to the cam shaft, crank shaft, and 30 other parts of the motor to be lubricated.

I provide a drip or collecting pan up above 35 the sump, and ducts leading downwardly from the pan to the sump, and in these ducts I interpolate a strainer unit of improved construction, this unit being adapted to be readily fitted on to the bottom of the crank case with the greatest facility. The crank case is formed with ducts leading downwardly 40 from the unit which is fitted thereto to the pump intake. In addition to the improvements in the cleansing of the lubricant, my invention has the advantages of simplicity in construction and of few parts, whereby the assembly thereof and the fitting of the 45 same to the crank case may be accomplished at a minimum expenditure of time and labor.

My improved lubricating devices, including strainer units and the drip pan, also have the advantage of being readily standarized 50 and the manufacturing cost thereof reduced to a minimum. For a better understanding of my invention, including the features above noted and others which will herein-after appear, reference may be had to the 55 accompanying drawings wherein:

Fig. 1 is a part sectional and part elevational view of a motor embodying my invention.

Fig. 2 is an enlarged view of certain parts thereof, 60

Fig. 3 is a plan view corresponding to Fig. 2, 65

Fig. 4 is a plan view of the lower half of the crank case, and

Fig. 5 is a sectional view thereof, 65

Referring to the drawings wherein like numerals refer to similar parts throughout, I have illustrated my invention as embodied in a V-type internal combustion engine of well known construction, only one bank of 70 the cylinders being illustrated. The framework or crank case of the engine comprises an upper half 1 having the cylinders 2 mounted in the form of a V thereon and having in the upper part thereof a hollow 75 camshaft 3, and below the camshaft, the usual crank shaft, this crank shaft also being hollow for the distribution of the lubricant therethrough and to the bearings. The camshaft 3 and the crankshaft 4 are 80 conveniently journaled within bearing supports 5 preferably formed integrally with the crank case, these supports 5 being provided as indicated with ducts 6 leading downwardly from the annular chambers 85 around the camshaft bearings downwardly to the crank shaft bearings. The lower half of the crank case 7 is adapted to fit as usual against the upper half and is provided with an oil pump in the lower part thereof as indicated for receiving the lubricant from the moving parts of the motor. The lower half of the crank case has mounted longitudinally thereof a drip pan being adapted to completely close the oil sump against the 90 upper part of the crank case, except through passages hereinafter set forth. For supporting this drip pan the lower half is provided with lugs 9 extending inwardly on the wall thereof. The drip pan is preferably made of sheet metal or aluminum and is provided with transverse bracing members 10, these bracing members being in the nature of U-beams, which may also be of sheet metal. These beams or bracing mem- 100 bers 10 may be provided with a plurality of apertures or holes 11 for the purpose of lightening the same. It is noted also that the drip pan is slightly curved in section at its middle with the concave side upward 110

and is provided midway of its ends with a convex portion 12, this being convexed upwardly to accommodate the lubricant pump as hereinafter set forth. The lower half of 5 the crank case 7 is provided with an opening in the bottom of the sump, into which is adapted to be fitted a drain and force pump 15. This pump may be of the type and structure set forth in my application filed 10 September 18, 1915, and since issued as Patent No. 1,286,345, which embodies a drain pump for draining the lubricant downwardly from the drip pan and also a force pump for withdrawing the lubricant from 15 the sump and forcing the same upwardly to the lubricating ducts supplying the moving parts of the motor. The duct leading upwardly from the force pump is indicated at 16, it being understood that this duct leads 20 to a connection 17 on the end of the cam-shaft which is made hollow for the purpose of serving as a lubricant distributing head. The drain pumps are indicated at 18, the one on the left leading to a chamber 19 25 formed on the end of the lower half of the crank case and enclosed by means of the end plate 20. A right hand duct 18 leads upwardly to a duct or passage 21 formed integrally in the crank case, this duct or 30 passage communicating with a slot or opening 22 formed in the end of the drip pan 8. Interpolated in the drain pipes 18 is a novel strainer unit comprising a pair of strainers 23 whose frames are preferably formed integrally with each other. Each of these 35 strainers comprises a cylindrical wall 24 and a pipe connection 25 leading through the side thereof for connection with the drain pipes 18. Each strainer is provided 40 with a cover 26 which fits tightly upon the top thereof and is secured thereby by a thumb nut 27, the latter engaging a rod or bolt 28 extending upwardly through the bottom of the strainer and through the center thereof. Surrounding this bolt 28 is a 45 cylindrical chamber for the purpose of providing an annular chamber 30 around the exterior thereof, the construction of the carrier for this filter being hereinafter set forth. Each strainer is also provided with a downwardly extending mouth or boss 32. An opening or passage 33 therein communicates at its upper end with the interior of the strainer 29 and at its lower end with a 55 duct formed in the crank case. Each cover 26 is provided with a downwardly extending member 34 which serves as a carrier for the filter 29. This carrier 34 comprises an upper ring 35' and a lower ring 35 which 60 are joined by integrally formed vertical ribs 34' as indicated. The upper ring 35' bears against a shoulder 31' formed on the interior of the cylindrical wall, whereby the unit is maintained in its proper position. 65 The two units 23 are provided with a bridge

36, joining the two bosses 32, which is formed at its under side with a seat complementary to the seat on the top of the member 37 formed on the crank case, it being understood that this member 37 has a couple of passages registering with the passages 33 of the strainer unit, these passages 38 leading to similar passages formed in the drain pump structure, whereby in the operation of this pump, the lubricant is forcibly 70 drawn through the strainer unit and carried upwardly through the pump to the oil sump as set forth more in detail in the above mentioned application. The duplex strainer unit may be secured in position by suitable 75 bolts 41 and to remove the unit as a whole it is only necessary to remove these bolts and disconnect the ducts 18. The filter 29 and carrier 34 are removable as a unit with the cover 26 for cleansing. 80

The operation of my invention is apparent from the above description. As before stated the pump 15 is of a plural pump structure the details of which form no part of the present application. The drain pump, 85 which is a part thereof, serves to draw the lubricant downwardly from the ends of the upper half of the crank case and above the drip pan through the ducts 18 and thence through the strainers 23. The pump outlets indicated at 40, return the lubricant to the sump and from the sump a force pump, 90 which is also a part of the plural pump structure, withdraws the same therefrom and forces it upwardly through the ducts 16 100 for distribution to the lubricating circuits. The oil is thoroughly cleansed in its passage through the strainers and may be used over and over again with perfect safety. 95

In accordance with the patent statutes I 105 have set forth one complete embodiment of my invention, but it is understood that the invention is capable of assuming various forms and proportions, and the claims annexed hereto are not to be limited to the 110 specific devices illustrated in the drawings, except as is specifically recited therein, but are to be construed in accordance with the real scope of the invention, due regard being had to a consideration of the prior art. 115

What is claimed is:

1. In an internal combustion engine, in combination, a crank case having an oil sump in the lower part thereof, a drip pan disposed within said crank case and between 120 said oil sump and the crank case, a lubricating pump disposed in the bottom of said sump, lubricating ducts leading downwardly from the ends of said drip pan to the suction end of said pump and a detachable strainer 125 unit interpolated in said communicating ducts and adapted to be attached to the lower part of the sump along side of said pump.

2. In an internal combustion engine, in 130

- combination, a crank case having an oil sump in the lower part thereof, said sump having formed integrally therewith a pair of communicating passages, a strainer unit 5 having outlets adapted to be attached to said sump in register with said communicating passages, communicating ducts leading downwardly from the ends of said crank case to said strainer unit, and a pump adapted to be fitted on to said sump in register with said communicating passages for the purpose set forth.
3. In an internal combustion engine, in combination, a crank case having an oil sump in the lower part thereof, a scavenging pump located in the bottom of said sump, a drip pan disposed above said sump, and adapted to catch the lubricant dripping downwardly from the moving parts of the 10 motor, a strainer unit adapted to be fitted to the bottom of said sump in register with the intake of said pump, communicating ducts leading downwardly from the ends of said drip pan to said strainer unit, and 15 means for forcing the strained lubricant to the moving parts of the motor.
4. A strainer unit comprising a cylindrical casting having a transverse inlet through the wall thereof and an outlet leading axially therefrom, a strainer corresponding in 20 shape to the cylindrical chamber of the casting and disposed therein, said cylindrical strainer and casting having spacing means for maintaining the same in alignment with the cylindrical casting, and means for attaching a cover to said cylindrical chamber for the purpose set forth.
5. In an apparatus of the type set forth, in combination, a strainer, a crank case unit 25 comprising a pair of strainer chambers formed integrally with each other, and car-
- ried within said crank case, said chambers having outlets and inlets therein for circulating the lubricant therethrough, and strainer members adapted to be readily inserted in and withdrawn from said chambers.
6. In an internal combustion engine, in combination, a crank case having an oil sump in the lower part thereof and a drip pan disposed above said sump, said crank case also having oil collecting chambers at either end thereof which are adapted to collect the lubricant draining downwardly to and from said drip pan, a scavenging pump 50 located in the bottom of said sump, communicating ducts leading from said scavenging pump to said chambers, and an integrally formed strainer unit adapted to be interpolated in said ducts and disposed with 55 their outlets at a point adjacent the intake of said scavenging pump, said scavenging pump having its outlets in communication with the interior of said sump.
7. In an internal combustion engine, the 60 combination of a crank case with a drip pan therein, said drip pan being provided with a longitudinal depression and being carried by lugs on the interior of said crank case and embodying transverse strengthening and bracing beams which are rigidly secured thereto and which extend across the depression.
8. In an internal combustion engine, a 65 crank case having a drip pan therein, said drip pan having its sides flat and its middle portion curved in transverse section, said drip pan also having transverse bracing and strengthening beams of U-shaped section.
- In testimony whereof I hereunto affix my 70 signature.
- CHARLES B. KIRKHAM.
